ATTORNEY

UNITED STATES PATENT OFFICE.

WILLIAM K. JOHNSON, OF WICHITA, KANSAS.

GUIDE.

Application filed April 16, 1924. Serial No. 706,975.

To all whom it may concern:

Be it known that I, WILLIAM K. JOHNSON, a citizen of the United States, residing at Wichita, in the county of Sedgwick and State of Kansas, have invented new and useful Improvements in Guides, of which the following is a specification.

This invention relates to an attachment for a sewing machine, the general object of the invention being to provide a guide for engaging the foot part of the machine and arranged to guide the embroidery floss or braid to the needle of the machine so that the floss or braid can be stitched to a piece of goods.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a view showing the device in use.

Figure 2 is a perspective view of the device.

Figure 3 is a bottom view thereof.

In these views, 1 indicates the foot of the sewing machine and 2 the needle thereof.

The guide is shown at 3 and consists of a plate having an extension 4 at one side thereof which is bent to form a loop to engage the left hand fork of the foot. The plate is provided with a substantially

V-shaped notch 5 at one end thereof to permit the passage of the needle and its other end is provided with a substantially inverted V-shaped bent finger 6 and a substantially V-shaped notch 7 which act to

guide the floss to the notch 5 and under the needle. The substantially V-shaped notches are oppositely disposed with their axis parallel with the line of feed and together with the finger 6 which is disposed in ad-

vance of the notched portion as shown, provide an adequate guide, the use of which will be presently described.

From the foregoing it will be seen that when the device is placed on the foot of a

sewing machine with the notch 5 arranged adjacent the needle, and embroidery floss or braid is threaded through the device by passing it under the finger 6 and through the notches 5 and 7, the floss will be guided under the needle so that the needle will pass through it and thus stitch the floss or braid to a piece of goods. The needle should be threaded with the thread of the same color as the floss or braid. The material to be embroidered is placed under the foot of the sewing machine the same as for ordinary sewing and the lines of the stamped pattern are followed the same as for any other embroidery work. The device is held in place by friction of the looped part on the prong of the fork.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. An attachment for sewing machines comprising a plate provided with oppositely disposed substantially V-shaped notches with their axis parallel to the line of feed, said plate having a looped part for engaging a prong of the foot of the sewing machine, and guiding means arranged in advance of the V-shaped notched portions and parallel to the line of feed whereby a material passing through is automatically centered with respect to the needle.

2. An attachment for sewing machines comprising a plate provided with oppositely disposed substantially V-shaped notches with their axis parallel to the line of feed, said plate having a looped part for engaging a prong of the foot of the sewing machine, and an inverted substantially V-shaped finger arranged in advance of the V-shaped notched portions whereby a material passing through is automatically centered with respect to the needle.

In testimony whereof I affix my signature.

WILLIAM K. JOHNSON.
